UNITED STATES PATENT OFFICE.

ALEXANDER CHRISTIE, OF SEATTLE, WASHINGTON.

HASP FASTENER.

Application filed August 7, 1924. Serial No. 730,572.

To all whom it may concern:

Be it known that I, ALEXANDER CHRISTIE, a citizen of the United States, residing at Seattle, in the county of King and State of Washington, have invented a certain new and useful Improvement in Hasp Fasteners, of which the following is a specification.

My invention relates to improvements in hasp fasteners for doors and is an improvement upon the hasp fasteners disclosed in my United States Letters Patent No. 1,240,316 issued September 18, 1917.

The objects of my invention are to simplify the construction of hasp fasteners and render the same more reliable and efficient in operation.

Other objects are to provide a hasp fastener having a coil spring that is arranged to engage with and press against two doors at their adjacent edges to hold said doors firmly closed and to prevent them from rattling; to provide a hasp fastener having a key operated lock in connection therewith; and to provide a hasp fastener having two bolt members arranged to be connected directly with the hand hold of the hasp fastener and to be operated thereby to lock the doors at the bottom and top thus affording a three point lock.

I accomplish these objects by devices illustrated in the accompanying drawings, wherein—

Figure 1 is a fragmentary view in elevation of two swinging doors showing my hasp fastener installed thereon and in a locked position;

Fig. 2 is a sectional view on a larger scale taken on line 2, 2 of Fig. 1;

Fig. 3 is a sectional view taken on line 3, 3 of Fig. 2;

Fig. 4 is a fragmentary view in elevation taken on line 4, 4 of Fig. 2 showing the inner side of the bolt mechanism as it might appear if detached; and

Fig. 5 is a detached view in side elevation of the member with which the hasp latch engages.

Referring to the drawings, throughout which like reference numerals indicate like parts, I have shown a hasp fastener and door lock embodying a hasp member 10, preferably of channel-shaped cross section and pivoted at one end by a pin 11 to a bracket 12 that may be secured to a door 13.

The hasp 10 is provided at the other end with a combined handle and latch member

consisting of a stem 14 rotatably mounted in the hasp, a cross bar 15 forming a hand hold on the outer end of the stem and a flattened tapered portion on the inner end of the stem having two lugs 16 arranged to lock into notches 17 in a bracket member 18 that is adapted to be secured as by screws 20 to a support, as another door 21. The bracket member 18 has an elongated opening 22 through which the flattened inner end of the stem 14, including the lugs 16, may enter when the hand hold 15 is parallel with the hasp, the lugs 16 being arranged to snap into the notches 17 when the hand hold 15 is turned after said lugs have passed through the elongated opening 22.

The bracket member 18 is provided with an integral locking lug 23 affording a shoulder 24 behind which a bolt 25 of a key operated lock 26 may engage to lock the bracket 18 and hasp 10 together if desired, the lock being mounted within and secured to the hasp and having a key plug cylinder 27 that projects through a suitable perforation in the hasp and is accessible from the front side of the same. In addition to this locking feature the lug 23 on the bracket 18 is arranged to project through a slot 28 in the hasp 10 and has a perforation 30 through which any holding or locking device as a padlock shackle may be passed to prevent the doors from being opened.

The hasp member 10 is provided about midway between its two ends with a coil spring 31 secured thereto by a rivet 32 so that it will project inwardly and having a flattened inner end arranged to press against the two doors 13 and 21 to hold such doors firmly and prevent any rattling of the doors or parts of the hasp fastener.

Means for bolting one of the doors at both top and bottom is provided, said means comprising two long bolts 33 and 34 secured to a cross arm 35 that is provided in a bracket 36 that is arranged to be fastened to the side of the door 21 opposite the bracket member 18, the cross arm 35 having a hub portion 37 provided with an elongated opening 38 into which the end of the inner end of the stem 14 is arranged to project when the hasp 10 is in the locked position.

In operation the hasp fastener may be used without using the lock 26 or without using any fastening or locking device in the perforated lug 23, or the lock may be used or the fastening device in lug 23 may be

used or both lock and fastening device may be used.

When unfastened the hasp permits both doors to open freely. Upon closing the doors the hasp is engaged by pushing inwardly on the handhold 15, compressing the spring 31 and turning the handhold 15 into a parallel position relative to the hasp to cause the lugs 16 to drop into the recesses 17 in the bracket 18.

When the handhold 15 is pressed inwardly the inner end of the stem 14 enters the elongated hole 38 in the hub of the cross arm 35 and when the handhold is turned to lock the hasp the cross arm 35 is also turned and projects the bolts 33 and 34 outwardly locking the door 21 at both top and bottom. Turning the handhold 15 back into a position parallel to the hasp 10 releases the lugs 16 and at the same time retracts the bolts 33 and 34 leaving the doors free to be opened unless they have been locked by lock 26 or by inserting some devices through the perforation in the lug 23.

The door 13 may be provided with a cleat 40 over which the edge of the door 21 may close so that the locking of the door 21 at the top and bottom by bolts 33 and 34 will also lock the door 13.

The spring 31 maintains a constant pressure on the two doors 13 and 21 and keeps all parts of the hasp under tension thus taking up all play between the various working parts and preventing the same from rattling.

The hasp fastener is shown applied to double doors but it is obvious that the same may be applied to a single door if desired where it will operate in the same manner.

The foregoing description and accompanying drawings clearly disclose a preferred embodiment of my invention, but it will be understood that this disclosure is merely illustrative and that such changes may be made as are within the scope and spirit of my invention.

What I claim is:

1. In a hasp fastener of the class described, the combination with two swingingly mounted doors of a hasp member pivoted at one end to one of said doors, latch members for securing the other end of said hasp member to the other door, and a helical compression spring secured to said hasp member, and projecting inwardly therefrom and arranged to be pressed against the adjacent edges of both of said doors when said doors are closed.

2. A hasp fastener embodying a hasp member pivoted at one end to one door, latch means for securing the other end of said hasp member to another door, a lock for locking the last named end of said hasp member to said last named door, and a heli-

cal compression spring secured to said hasp member and projecting inwardly therefrom and arranged to be pressed against the adjacent edges of both of said doors.

3. In a hasp fastener of the class described, a hasp member arranged to be pivoted at one end to a support, a bracket member arranged to be secured to another support, said bracket being slotted, a shank pivoted in the free end of said hasp member and extending crosswise thereof, a handhold on the outer end of said shank, latch members projecting sidewise from the inner portion of said shank and arranged to engage with and lock into said bracket when said shank is thrust into said bracket and turned, a locking member on said bracket, a key operated lock arranged to engage said locking member, and a spring carried by the inner side of said hasp member for yieldingly engaging the supports with which said hasp is connected when said hasp is in a locked position.

4. In door fastening devices of the class described, bolts for locking a door, a hasp pivoted at one end, latch means on the other end of said hasp, and devices connected with said latch means for operating said bolts when said hasp is in a locked position.

5. In door fastening devices of the class described, bolts mounted on the inside of a door, a hasp mounted on the outside of the door, and latch means on said hasp arranged to engage with said bolts for operating the same when said hasp is in a locking position.

6. In door fastening devices of the class described, a hasp pivoted at one end to a support, latch means for securing the other end of said hasp to a door, and bolts on said door arranged to be operated by said latch means when said hasp is in a locking position, said bolts being free of said latch means when said hasp is not in locking position.

7. In door fastening devices of the class described, a hasp member pivoted at one end to a support, a bracket arranged to be secured to the outside of a door, a shank rotatably mounted in the free end of said hasp and having latch members for engaging with said bracket, a lever arm pivoted to the inside of said door opposite said bracket, bolts secured to said lever arm for locking said door at the edges and arranged to be moved outwardly and inwardly by movement of said lever arm, and means on the inner end of said shank for operatively engaging said lever arm when said hasp is in locking position.

In witness whereof, I hereunto subscribe my name this 1st day of August, A. D. 1924.

ALEXANDER CHRISTIE.
